MARK THOMAS DENNE, OF LONDON, ENGLAND

SOLE ROUNDING OR TRIMMING AND CHANNELING MACHINE

Application filed June 8, 1925, Serial No. 35,542, and in Great Britain June 11, 1924.

This invention has reference to improvements in and relating to sole edge trimming or trimming and channeling machines whereby an "extension edge" may be produced and in which latter machines the channel knife is automatically adjustable so that the channel may be cut further from the sole edge at the shank than at the forepart.

As heretofore constructed, machines of the kind referred to are in several respects seriously defective, the cumulative effect of which is that the machine cannot be run at the high speed now called for, and the necessary adjustments of the several parts to adapt the machine for operating on different styles of shoes (which term shoes is intended to include boots) are so difficult to make that much time is thereby taken up, thus still further militating against a desired high output.

The main object of my invention is to obviate these defects, other objects being to improve individual parts or mechanism of the machine as will be pointed out.

Machines of the type to which my invention more particularly relates, includes a work rest, a reciprocating trimming knife, means to feed the work intermittently forward, an adjustable work guide (or guides) that assists in guiding the work relatively to the plane in which the trimming knife operates, and means whereby the guide may automatically be moved in the direction perpendicular or transverse to said plane. For channeling, there is provided an adjustable channel knife and means connected with the work guiding means so that the said knife will automatically be adjusted to cut the channel further from the sole edge at the shank than at the forepart.

The aforesaid transverse movement of the work guide (usually a last guide) has heretofore been a step by step or intermittent movement (brought about by intermittently rotating a disc cam that controls the guide) the guide being stationary whilst the trimming knife is cutting or still engaged in the sole and being moved only during the comparatively brief periods that said knife is disengaged from the sole.

Such a construction or arrangement itself is seriously defective in several particulars.

In the first place to produce the intermittent movement of the disc cam, comparatively delicate pawl and ratchet mechanism is provided to rotate intermittently the arbor on which the cam is mounted, and this delicate mechanism is duplicated so that the necessary reverse movement (for right and left shoes) may be produced. In some cases a friction device is provided so that the pawl and ratchet shall not be subjected to undue strain. Further, as will be pointed out hereinafter, the use of a disc cam, having its periphery formed as a cam surface, for the purpose stated, also leads to difficulties at times.

An object of my invention is to obviate these defects.

As a result of experiments and tests carried out under factory conditions I find that taking advantage of the natural elasticity of leather I am enabled to employ means, such as a cam, which imparts constant or continuous movement to the work guide, so that the guide is moved (according to the shape of the cam) whether the trimming knife is in the work or not.

This at once considerably simplifies an important part of the machine because the delicate pawl ratchet mechanisms as well as the mechanism to actuate them in timed relation with the reciprocating trimming knife is rendered unnecessary. By this simplification this part of the machine can be made much stronger and may be driven with safety at a much higher speed.

To this end therefore my invention consists broadly in a machine of the type referred to in which continual movement is imparted to the work guide for the purpose stated.

A further defect in machines of the type in use concerns the means whereby variations in the shape of the extension edge may be produced.

In one well known machine this is effected by an intermittently rotated disc cam (that controls the work guide) and means whereby the extent or degrees of each small rotary movement may be regulated. The regulating mechanism is complicated and delicate.

In another, also well known, machine, a number of disc cams of different shapes are mounted on a common arbor (to which intermittent rotary movement is imparted as described above) which is so constructed and mounted that the operator can move it in the longitudinal direction and bring into the operative position any one of the cams, means being provided to lock the arbor, after adjustment, against longitudinal movement.

Apart from the mechanical complications involved there is the serious disadvantage that disc cams are difficult to make and fairly costly.

It happens quite frequently that a shoe manufacturer is requested to supply a small quantity (perhaps a dozen pairs) of shoes, the extension edge of the soles of which are of a special shape which cannot be produced by the use of the disc cams supplied with the machine.

Only a very skilled operator would be able to produce a pair or may be two pairs of shoes by moving the work guide manually so that the correct shape is given to all the soles. To produce a dozen pairs in that manner, all the twenty-four soles of which are perfectly matched, would be beyond the power probably of the most skilled workman. Further, there are many shoe factories in which such a highly skilled operator is not available and in any event the cost of producing the shoes would be increased considerably.

The only alternative is to have a disc cam of appropriate shape specially designed and made so that it can be substituted for one of those on the cam arbor. This again means considerable expense and probably delay also.

It will therefore be realized that if these defects can be overcome an important advance will have been made both as regards avoiding an appreciable increase in the cost of production and in loss of time producing the shoes and the provision of means whereby this difficulty may be obviated is another object of my invention.

To this end I dispense altogether with the use of disc cams for the purpose stated and provide flat plates one edge of which is shaped as a pattern or profile cam and which plates are supported and moved so that their shaped edge controls the work guide.

The shape given to said edge will be similar or approximate to that of the extension edge that will be produced by its use and if the cam or profiled portion extends above the median line of the plate there may be a line or lines representing the side of the last so that the operator can at once see what shape of extension edge he can produce by it. There will be a number of such pattern cam plates supplied with the machine and these will preferably be made of metal. Should the shoe manufacturer receive an order for a small quantity of shoes the soles of which

are to have a special shape, a pattern cam made of wood, preferably hard wood, would be quite serviceable and this could be fashioned by any reasonably intelligent workman. The suppliers of the machine could at very small cost supply a number of such hard wood pattern cams, the shaped edges of which are left sufficiently full to permit the workman by filing, rasping, or other means, to make the necessary alterations and thus quickly fashion the edge to the desired form.

By these means considerable time and money may be saved and the output of the machine maintained.

A further serious defect in machines of the type referred to (when provided with channeling means) as heretofore constructed is that neither the precise or exact adjustment of the channel knife to position this relatively to the plane of operation of the trimming knife, nor the precise or exact adjustment of the automatic means whereby adjustment of the channel knife relative to said plane may readily be effected during the operation of the machine.

A further object therefore of my invention is to obviate these defects and to this end my invention consists in coupling or linking up the adjustable channel knife with a part that is readily accessible for adjustment and by the adjustment of which the position of the channel knife is regulated and by the automatic movement of which the position of the said knife may be changed during the trimming operation.

The foregoing generally describe the main features of my invention as affecting the principal mechanisms of the machine.

Certain other features to be described hereinafter, including among others the means for supporting and adjusting the forepart guide; the means for supporting and moving the pattern cam; the means for reversing the movement of the pattern cam; and other devices and mechanisms also, conspire to the attainment of the objects or at least the main object of my invention.

The preferred constructional form to be described of the complete machine also forms an important feature of my invention.

The preferred constructional form of my invention is illustrated in the accompanying drawings in which Fig. 1 is a front elevation of the complete machine drawn to a comparatively small scale; Fig. 2 is a front elevation and Fig. 3 a side elevation of the head of the machine and the mechanism carried by it; Fig. 6 is a section on line C—D of Fig. 3; and Figs. 4, 5, 7, 8, 9, 10, and 11, illustrate details to be referred to.

In said drawings the numeral 1 indicates the machine head which is mounted on a standard 2 in the usual manner. The head is provided with ball thrust and journal bear-

ings 3 that support a cam shaft 4 on one end of which the usual fast and loose belt pulleys 5 and 6 are carried and whereby the machine may be driven from a suitable source of power. The cam shaft 4 is supported so that it is perpendicular with respect to the direction of the work feed movement, the latter being as usual in the plane of the front of the machine, and said shaft carries a cam drum 7 having cam grooves 8, 9, 10, and 11, by which movement in timed relation is imparted to the various mechanisms to be described.

In my machine there is no additional cam shaft which heretofore has been found necessary to carry, in some machines, a number of cam discs by one or other of which the forepart guide is to be automatically intermittently actuated, and therefore the rather complex means whereby the said additional cam shaft may be adjusted to bring the required cam disc into operative position and to retain it in adjusted position and then intermittently rotate it, are also dispensed with.

On a suitable bearing 12 I provide a horizontal frame 13 that contains a bar 14 of preferably rectangular section. The bar at its front end is provided with a depending abutment 15 on which is secured a copper or other suitable plate 16 to serve as a cutting block. This depending abutment is located within and projects through a crease guide 17 of about usual construction, and the bar is moved longitudinally to a slight extent at the appropriate moments—this being effected by the cam groove 8 which is engaged by a cam roll 18 on a stud 19 secured to the bar—so as to be clear of the work when this is being fed along. As the cutter block must not yield, for the reason stated, when the edge trimming knife is in operation, the depending abutment and its support referred to must be made very strong and the construction hereinafter to be described of the forepart guide enables this to be done within a minimum space.

The frame 13 referred to is adapted to be rocked so that the abutment 15 moves to feed forward the work (acting for this purpose in conjunction with the channeling knife and its support, as will be described), and for this purpose (see Figs. 3 and 4) I provide a cam roll 20 that engages in the cam groove 10 and which is carried by a stud 21 on a sliding bar 22 moving in guides 23 in the main frame or head and connected at its forward end to a lever 24 that is fixed on a vertical cylindrical stem 12, the upper end of which is formed or provided with the frame 13. The rear end of the bar 22 is provided with a fin 25 that projects between cheeks 26 of a bearing whereby rotary movement of the bar 22 is prevented.

At a suitable position I provide a guided slide bar 27 that has clamped to its front

end a sole edge trimming knife 28 there being also provided the usual vertical chisel or like member 29 that engages in the trimmed off part of the sole to assist in holding the shoe whilst the channel knife operates. The bar is provided with a stud 30 carrying a cam roll 31 to engage a cam race 9 in the drum and by which reciprocating movement, in timed relation with the work feed, is imparted.

Below the bar 27 carrying the edge trimming knife is provided (Figs. 2, 3 and 5) a horizontally slideable member 32 which is provided at its front end with vertical slideways 33 on which fits a slideable channel knife holder 34, the knife 35 being clamped to the holder by any suitable means. The slideable member is rocked at the proper times so that the channel knife will assist in feeding forward the work. This is attained by the bar 32 being received in a bearing on a block 32^a that is secured to the vertical spindle 12, the arrangement being such that the channeling knife is free to be moved towards and from the shoe but is compelled to move in the direction of work feed movement together with the abutment 15 by reason of the block 32^a being secured to the spindle 12 by which lateral rocking movement is imparted to the bar 14 that carries the abutment 15.

The horizontally slideable member is normally pressed forward by means of two long springs 36, 37 so that they press the knife holder and the channel knife against the work, the long springs being employed so that a practically equal pressure will be exerted notwithstanding variations in the thickness of the work. By the use of these long springs the fairly complicated mechanism heretofore provided in machines of the class referred to, to obtain substantial equality of pressure as aforesaid, is dispensed with.

To move the said member (and with it the channel knife) rearwards, it is provided with a block 38 to receive the cylindrical end of a substantially vertical rocking lever 39 the lower end of which is connected by a link 40 to one arm of a bell crank lever 41 the other arm of which is acted on by a treadle controlled spring-pressed push rod 42, the arrangement being such that, when the treadle is depressed, the knife and its support are moved rearwardly to permit insertion or removal of the work.

To enable the workman readily to adjust the channel knife up or down so that he may determine the distance from the edge of the sole at which the channel is to be cut, and to effect the automatic adjustment of the knife so that the channel will be cut nearer to the edge around the forepart than in the shank, and to enable the automatic adjustment to bring about a variation from nil to the maximum, I provide the following:

The vertically slidable channel knife holder 34 has connected to it a link 43 which, at its lower end, is connected to one arm of a bell crank lever 44, the other arm of which engages a block 45 on the end of a horizontally slidable bearing or trunk 46, a similar trunk 47 being slidably supported in alignment with the trunk 46.

The second trunk 47 has a bearing 49 that supports the trunnions of a rocking lever 48, the front end of which is adjustably connected to a slide bearing 50 by means of fitting blocks 51. The slide bearing comprises a casing that is adjustably secured at any desired angle from the vertical to a predetermined maximum inclination.

The other end of the rocking lever 48 is engaged by means of a slide bearing 52, or dog, on the treadle rod 53 of a second treadle lever (and by which, as will be described, the forepart guide is to some extent controlled) and the bearing supporting the rocking lever is adjustable by a screw 55 provided with a hand nut 54, the arrangement being such that, when the workman turns the screw in one or other direction, he will bring about the adjustment of the channel knife up or down as he may desire. When the machine is in operation, the adjustment of the channel knife 35 will be automatically effected if the slide casing 50 has been set at an angle to the vertical and the amount of movement of the knife will depend upon the degree of angular adjustment of the slide casing. If this latter is adjusted in the vertical (or practically vertical) position, the channel knife will be held stationary. The workman can thus cause the knife to cut at a predetermined equal distance from the edge of the sole around the forepart and the shank (which may be desirable for some classes of shoes), or he may cause the channel to be cut at a greater distance at the two sides of the shank than around the forepart and he can determine the extent or degree of difference in the distance from the edge of the sole at the shank and the forepart at which the channel is to be cut.

The forepart guide 56 preferably consists of a metal blade that is bent into a more or less arcuate form and is supported by a rocking carrier 57 that has trunnions 58 or the like supported in bearings in the frame or head of the machine. The blade is arranged so that it may be adjusted relatively to the carrier according to the minimum width desired of the projecting edge of the sole, and it is held in adjusted position by suitable means. I prefer to provide for this purpose a worm 59 that engages in teeth 60 which are cut at one part of the blade 56 constituting the forepart guide so that when the workman, by rotating the worm, has adjusted the guide, the latter will be held against movement by the worm.

For the purpose of imparting automatic movement to the forepart guide when the "extension edge" is to be produced, I employ a cam or profile strip 61 (Fig. 11) having one edge of appropriate shape as will be described, and which strip I secure to a bearing 62 that is slidably transversely of the machine, and on a stud 63 secured to the rocking carrier 57 I provide a cam roll 64 that is adapted to be engaged against the shaped edge of the strip 61, so that, as the bearing and strip advance (or recede), the carrier, and therefore the forepart guide also, will move up or down so long as the roll is held against the cam strip. The movement of the cam strip in one direction will produce a movement of the forepart guide suited to produce the "extension edge" on the sole of one shoe, and the movement in the opposite direction will be appropriate for the other shoe of a pair.

The contour of the "extension edge" is of course determined by the shape of the profile cam strip for the time being in the machine, and therefore I propose to provide each machine with a set of cam or profile strips so that any one or other of the various shapes of "extension edge" usually demanded may be produced by merely placing in position the appropriate strip. These strips may be made of metal or even of hard wood and therefore they can be produced quite cheaply, so that a shoe manufacturer may readily provide himself with a strip of special form should he receive an order for shoes with an unusual shape or form of "extension edge".

It is very desirable that the strips may be quickly applied and removed and for this purpose I form each strip near each end with an aperture, and I provide the bearing with a pair of studs 65 to fit these so that the workman can, as it were, drop the strip on to the studs, and these latter will securely hold the strip whilst the bearing is moving transversely of the machine.

The carrier 57 on which the forepart guide is mounted is acted on by a spring 66 that tends to move or rock it so that normally the forepart guide and its support are well out of the way enabling the workman to have a clear view of the work gripping members. This will be the position of the guide when the waist of the shoe is being trimmed and when the shoe is being inserted in position in the machine.

To bring the forepart guide into action I provide a treadle, the rod 53 of which is connected to one arm of a suitably supported bell crank lever 67, the other arm of which is connected to a rod 68 that has a slide 69 on which an antifriction roll 70 is mounted and which, when the treadle is depressed, is forced against a cam surface 71 with which I pro-

vide the carrier 57 and whereby the latter will be rocked.

The transversely slidable carriage 62, on which the cam plate 61 is supported, is put into action by the operator's depressing a knob or button 72 (Figs. 1, 9 and 10), the position of which may be such that the operator may effect this depression with his knee and thus leave both his hands free to 10 manipulate the shoe. The depression of the knob operates gearing, comprising a rack 73, toothed wheels 74, and a second rack 75 on the lower end of a vertical rod 75^a, and this, acting through a tumbler 76 causes a worm 15 77 to be driven by one or other of two gears 78, 79 that rotate in relatively opposite directions, and which worm directly, or through the intermediary of toothed gears 80, 81, 82, imparts movement to the carriage 62.

20 Supported in suitable bearings are two sleeves 83, 84, on which crown wheels 85, 86, are respectively fixed and which two crown wheels are driven in relatively opposite directions by crown pinions 78, 79, deriving rotary motion from a constantly driven spindle 87, through suitable gears 88, 89, 90. If it be desired to stop the rotary movement of the crown wheels, the gear wheel 89 on the spindle 87 is moved longitudinally thereon to disconnect it from the two pinions 88, 90, it normally drives, and this disconnection may be effected automatically when the forepart guide is moved out of action, for instance by means of a connection with the bell and crank 35 mechanism 67.

The sleeves 84, 83 are provided respectively with toothed disc wheels or clutch members 91, 92, and passing centrally through the sleeves is a spindle 93 that carries at its ends 40 toothed clutch members 94, one or other of which is put in gear with the relative clutch members 91, 92 on the sleeves 84, 83 if the spindle that carries them is moved axially. Mounted on the spindle 93 midway of its 45 length (i. e., between the crown wheels referred to) is the worm 77 that is compelled to rotate with the spindle although the latter, for the purpose stated, may be moved in the axial direction without carrying the worm 50 with it, the arrangement being such that if the spindle 93 be moved axially in one direction the worm will be rotated clockwise by the connection of the clutch members 92 and 94, and anti-clockwise by the connection of the clutch members 91 and 94, if the spindle 55 be moved in the other direction.

For imparting movement to the spindle 93 in the axial direction, I provide a suitably supported slidable rod 95 having arms 96, 97 that project in proximity to the ends of the spindle 93, and said rod 95 has a block 98 formed with a preferably V-shaped recess 99 (Fig. 7), in which a roll 100, acted on by a spring 101, engages, and which roll normally serves to maintain the rod 95 in the

central position. Pressing on said block 98 is a spring pressed rod 102 that has a snug 103 which will engage in one or other of two recesses 104, 105, in said block so as to retain the rod in one or other extreme position (and thus maintain the clutch members 92, 94, or 91, 94 in gear) when it has been so moved. If said spring pressed rod 102 be raised to disengage the snug 103 from the recess 104 or 105, the spring pressed roll will at once 75 move the sliding rod 95 to its central position and thereby throw the clutch members out of engagement.

The foregoing is provided so that the operator need not hold the knob or button 72 depressed as a mere momentary depression thereof will cause the temporary locking of the parts as described.

When the worm 77 is thus rotated it moves the profile or cam strip supporting carriage 85 62 in one direction until one or other of two dogs 106, 107, comes into engagement with a central wedge block 108 on said rod 102 and which wedge device throws the locking means 90 out of action.

The next depression of the knob or button so operates the connecting and locking means that the worm will be rotated so as to move the carriage in the opposite direction.

The means whereby successive depressions 95 of the knob will bring about a rotation in relatively opposite directions of the worm for the purpose stated, preferably comprise a rocking block 109 (Figs. 9 and 10) to which the sliding rod 95 is connected and which 100 block has extensions between which and the lugs 114, 115, on the tumbler 76 referred to, slidable studs 111, 110, are provided so that when the tumbler 76 is rocked it will, acting through one or other of the studs, rock the 105 block 109 referred to and thus bring into action one or other of the arms 96, 97, on the sliding rod 95.

The tumbler 76 is acted on by a spring 110 plunger 112 having inclined surfaces at its end adapted to engage one or other of similar surfaces on the tumbler, the plunger also acting as a brake. The tumbler 76 is moved or rocked, when the button 72 is depressed, by a spring finger 113 which rides up one or other sides of the more or less V-shaped lower part of the tumbler until it engages one or other of the lugs or shoulders 114, 115, thereon and thereupon further movement of the finger will rock the tumbler. When the 115 spring finger 113 has returned to its normal position and is again raised, it will ride up the other inclined surface or side of the tumbler 76 and eventually rock this in the opposite direction.

When the tumbler 76 is rocked (in either direction) the spring plunger 112 will yield, thus allowing the tumbler to push the slidable rod (110 or 111) to swing the rocking block 125 and will then return a slight distance so that 130

the slideable rod does not offer any obstruction or resistance to the return of the rod to its central or inoperative position whilst permitting the tumbler to remain with the detent holding it in correct position for assuring that the spring finger will engage with the opposite angularly disposed face or surface on the tumbler so as to ensure, through the mechanism described, that the profile strip will be moved in the opposite direction.

It is desirable that the operator may know at a glance whether the machine is set to operate on a left or on a right shoe and for this purpose I provide a rotary disc bearing indicating letters L and R, and which disc is moved simultaneously with the tumbler by means of a lever 118 carried by the tumbler 76, the free end of which has a stud that engages in a slot in said disc.

20 The mode of operation is as follows:—

The operator first adjusts the edge trimming knife 28 to ensure that it contacts firmly with the cutting block when in its most forward position. He then adjusts the crease 5 guide 17 according to the minimum width of the projection sole edge he desires. Then, by turning the knob 54 he adjusts the position vertically of the channeling knife according to the distance from the sole edge at 30 which the channel is to be cut at the waist of the shoe and finally, by means of the hand nut on the spindle of the worm 59, he adjusts the forepart guide 56 and he places an appropriate profile plate 61 on the carriage 35 62 where it is held against movement by the pins or studs 65.

The operator then starts the machine and he depresses the treadle on rod 42 whereby the channel knife is moved to its rearmost position and then he inserts the shoe by holding this with its sole vertical and moving it up against the guide 17, the guide entering the crease or angle formed by the sole and the upper. He will thus present the 45 part of the shoe (at one or other waist) where the trimming and channeling knife are to commence and he will release the treadle rod 42 when the channeling knife will at once engage and cut into the sole, it being pressed thereagainst by the springs 36, 37. The trimming knife will trim the margin of the sole and the channel knife will, in addition to cutting the channel, feed the shoe, acting for this purpose in conjunction with the rocking movement of the block 15.

When the end of the waist is about or nearly reached, the operator will depress the appropriate treadle to raise the treadle rod 53. This will bring the work guide 56 60 against the shoe and, simultaneously, the cam roll 64 against the profile plate 61. Simultaneously with his depressing the treadle that controls the rod 53, the operator will depress, by his knee, the button 72 whereby 65 one or other of the clutch members 94 will

engage with the relative clutch members 91 or 92 and thus set the worm 77 rotating. The worm, through the gearing already described, moves the carriage 62 and with it the profile cam by which latter the extent and direction of movement of the work guide 56 is determined. By these means the "swell" or "bulge" on the sole edge is produced. When the carriage 62 reaches the end of its movement, one or other of the wedge blocks 106, 107, will engage the part 108 and will withdraw the part 103 from the notch 104 or 105 thereby allowing the spring 101 to bring the clutch members to their neutral position.

The foregoing will be suitable for operating on one shoe of a pair. When the other shoe is to be operated on the operator proceeds as before but when he depresses the button 72 the other clutch member (91, 92) than that previously engaged will be set in operation and the carriage 62 moved in the opposite direction.

If the channel is being cut too near or too far from the edge of the sole at the forepart the operator by adjusting the slide casing 50 90 may make the necessary correction.

Claims:—

1. A machine of the type described, having a work support, a trimming knife, means to reciprocate said knife, means to move the work intermittently in the plane of operation of the trimming knife, a work guide, and means placed in action by the operator and while in action moving the work guide continually in a direction transverse to the plane of operation of the trimming knife.

2. A machine of the type described having a work support, a sole edge trimming knife, means to reciprocate said knife in one plane, means to move the work intermittently in the plane of operation of said knife, a profile plate, means to impart continual movement to said plate, and a movable work guide controlled in its movement by said profile plate.

3. A machine as claimed in claim 2, and means to impart the continual movement to the profile plate in one direction when one shoe of a pair is operated on and in the opposite direction when the other shoe is operated on.

4. A machine of the type described having a work support, a sole edge trimming knife, means to reciprocate said knife, a work feed mechanism to feed the work intermittently in the plane of operation of the trimming knife, a work guide, a profile plate to determine the position of said guide, means put in action by the operator to impart continual movement to said plate, and a device automatically throwing the last referred to means out of action.

5. A machine as claimed in claim 4 in which is provided a worm and gearing actuated by said worm to move the profile plate, and means to rotate said worm continually in one or in the other direction.

6. A machine of the type described having a work support, a channeling knife, means to move the knife from and towards the work, means to effect the automatic adjustment of said knife during the operation of the machine, and means under the control of the operator whereby, during the operation of the machine, the said automatic adjustment may be varied for different styles of shoes. 5
- 10 7. A machine of the type described having a work support, a channeling knife, a trimming knife, a work feed mechanism, a profile plate to determine the position of the work relative to the knives, and means controlled by a treadle and said profile cam plate and adjustable during the operation of the machine to move the work and simultaneously the channel knife. 15
- 20 8. A machine as claimed in claim 7, in which is provided a mechanism comprising a slidable member 46 linked up with the channeling knife, a second slidable member 47 having a bearing 49, a rocking lever 48 supported in said bearing and connected at one end to the slidable member 46, and a screw device 55 for adjusting the knife during the operation of the machine. 25
- 30 9. A machine of the type described having a work support, a knife to operate on the work, means to feed the work, a movable work guide, a profile plate to determine the position of said guide, a carriage arranged for sliding movement to support said plate, means under the control of the workman to 35 determine the direction of movement of said carriage, and means supported by the carriage automatically to throw out of action the carriage moving means.
- 40 10. A machine of the type described having a work support, a knife to operate on the work, work feed mechanism, a movable work guide, a profile plate to control the movement of the guide, a constantly rotating spindle, a worm, means connecting the worm with the profile plate, crown wheels driven in relatively opposite directions by said spindle, means under the control of the operator whereby either one of the crown wheels may be made operative to rotate the worm, and means movable with the profile plate to throw the worm out of action. 45
- 50 11. For a machine of the type described, in combination, a work support, a trimming knife, a channeling knife, means co-operating with the channeling knife to feed forward the work, a carriage arranged for movement in a plane parallel to the work feed movement, a work guide arranged to be put into action by the operator and movable in a plane perpendicular to the first plane, and a pattern cam on said carriage to control the movement of the guide. 55
- 60 12. A machine of the type described having a work support, a trimming knife, a channeling knife, means to feed forward the work, 65
- an adjustable work guide, a carrier for said guide, a cam roll on said carrier, a profile plate to be engaged by said roll, and means to impart continual movement in a rectilinear path to said plate. 70
13. For a channeling machine, in combination, a work support, a channeling knife, a slidable member operatively connected with said knife, a slide casing adjustably secured to said member, and connections to the casing arranged for actuation by the operator to vary the position of said knife. 75
14. For a channeling machine, in combination, a work support, a channeling knife, a slide member operatively connected with the channeling knife, and means comprising a slide casing, supported for angular adjustment by said member, and an operating member, engaged with said slide casing, by operation of which the knife is moved a distance dependent upon the angular adjustment of the slide casing. 80
15. A machine of the type described having a work support, a sole edge trimming knife, means to impart reciprocating movement to said knife, a work guide movable in either direction relatively to the plane of movement of said knife, and a profile plate movable in a rectilinear path in one direction to cause said guide to be moved first in one and then in the opposite direction during such rectilinear movement. 85
16. For a machine of the type described, a work support, a knife holder, a channeling knife mounted on said holder, a slidable member, connections between said member and said holder, automatic means to impart movement to said member, and means to adjust said member independently of the means whereby its automatic movement is effected. 90
17. For a machine of the type described, a work support, a knife holder, a channeling knife mounted on said holder, a slidable member, connections between said member and said holder, an adjustable slide bearing mounted on said member, a rocking lever one end of which is slidable in said bearing, and automatic means to rock said lever. 110
18. For a machine of the type described, a work support, a trimming knife, work feed mechanism, an adjustable work guide, a profile cam plate to control the position of said guide, a slidable carriage to support said plate, means to position and hold said plate on the carriage, mechanism to impart movement to said carriage, two oppositely continually driven members, and means under the control of the operator whereby he may operatively connect either of said members to said mechanism. 115
19. For a machine of the type described, a work support, a trimming knife, work feed mechanism, an adjustable work guide, a profile cam plate to control the position of said guide, a slidable carriage to support said 120

plate, means to position and hold said plate on the carriage, means including a slidable spindle to impart movement to said carriage, two clutch members mounted on said spindle, other members rotating in relatively opposite directions, a tumbler, a rocking block moved by said tumbler, connections between said block and said spindle, and means to rock said tumbler.
